UNITED STATES PATENT OFFICE.

FRANK J. REAVES, OF ROCKFORD, ILLINOIS, ASSIGNOR TO THE ROCKFORD WATCH COMPANY, LIMITED, A CORPORATION OF ILLINOIS.

DOUBLE ROLLER FOR BALANCE-ESCAPEMENTS.

SPECIFICATION forming part of Letters Patent No. 740,179, dated September 29, 1903.

Application filed August 23, 1902. Serial No. 120,735. (No model.)

To all whom it may concern:

Be it known that I, FRANK J. REAVES, a citizen of the United States, residing at Rockford, in the county of Winnebago and State of Illinois, have invented certain new and useful Improvements in Double Rollers for Watch-Escapements, of which the following is a specification.

This invention relates to that class of mechanisms known as the "escapement of watches," and particularly to a double roller to be used in connection therewith, all of which will more fully hereinafter appear.

The principal object of this invention is to provide a simple, economical, and efficient double roller for watch-escapements, made in two parts and arranged to be detachably secured together, so that it may be separated easily and always assembled in correct relation.

Further objects of the invention will appear from an examination of the drawings and the following description and claims.

The invention consists principally in a double roller for watch-escapements, made in two parts detachably secured together, and means for assisting in the assembled relation of such parts to hold them in correct relation.

The invention consists, further and finally, in the features, combinations, and details of construction hereinafter described and claimed.

In the accompanying drawings, Figure 1 is a plan view of an escapement having a double roller constructed in accordance with these improvements; Fig. 2, a side elevation of the same; Fig. 3, an enlarged sectional elevation taken on line 3 of Fig. 1, illustrating a roller constructed in accordance with these improvements; Fig. 4, a plan view of the lower flange on the roller proper looking at it from below, and Fig. 5 a plan view of the main or lower portion of the roller looking at it from above.

In the art to which this invention relates it is well known that a double roller is very advantageous in that better adjustments of time can be made, owing to the fact that the roller-jewel can be located at the maximum distance from the axis of the balance-staff. It therefore becomes desirable to make a dou-

ble roller which will have this advantage and the additional one of being easily separated for purposes of repair, renewal, and adjustment, all of which will be understood and appreciated by those skilled in the art.

In making a roller in accordance with these improvements I provide a main or lower portion *a*, having an upwardly-extending roller-jewel *b* located therein at its maximum distance from the axis of the staff-opening *c* in such roller. This main or lower portion is also provided with a circular recess *d* in the upper face thereof, having a dowel-pin hole *e* extending therethrough. I next provide a roller portion proper, *f*, having a passing hollow *g* therein arranged opposite the roller-jewel, and an integral downwardly-extending tubular portion *h*, provided with a circular flange *i* at the bottom thereof. This circular flanged portion is of a size to snugly fit the upper recess *d* in the lower portion of the roller and is further provided with a dowel-pin *k*, arranged to fit the dowel-pin hole in such recess.

In operation the roller is placed on the balance-staff *t* and the usual pallet *l* and fork *m* are supplied, operating with the rest of the escapement and watch-train, all of which is old and well known in the art and needs no further or detailed description here. The fork has the slot and horn portions *n* at the front portion engaging with the roller-jewel and is further provided with a dart *p*, arranged when the parts are in the position shown in Fig. 1 to rest in the passing hollow and at other times on the periphery of the roller proper until such roller rotates backward and releases the same, all of which is well known and understood by those skilled in the art.

The roller or different parts thereof may be placed together and brought into correct relation without any fitting or may be separated for the purposes of repair, renewal, or adjustment with the assurance that they can be reassembled in the correct relation.

I claim—

1. In a double - roller escapement for watches, a balance - staff, a double roller formed in two parts detachably secured together, and means for assisting in the assem-

bled relation of such parts to hold them in correct relation, substantially as described.

2. In a double - roller escapement for watches, a balance - staff, a double roller formed of a main portion carrying a roller-jewel, a supplementary disk portion provided with a passing hollow, a tubular portion detachably connecting both of such portions, and means for holding such portions in correct relation, substantially as described.

3. In a double - roller escapement for watches, a balance-staff, the combination of a main portion provided with a roller-jewel extending upwardly therethrough, a disk portion of smaller diameter provided with a passing hollow, an integral tubular portion extending downwardly therefrom having a flange in its lower portion, and means for

holding such parts in correct relation, substantially as described.

4. In a double - roller escapement for watches, a balance - staff, a double roller formed of a main portion carrying an upwardly-extending roller-jewel and a circular recess in its upper portion, a disk roller of smaller diameter provided with a passing hollow and an integral tubular portion extending downwardly therefrom and having a circular flange at its lower end fitting the circular recess in the main portion, and dowel-pin mechanism for holding such parts in their correct relation, substantially as described.

FRANK J. REAVES.
